(57) **CLAIM**

The ornamental design for a fluid pressure cylinder tube, as shown.

DESCRIPTION

FIG. 1 is a bottom and left front perspective view of a fluid pressure cylinder tube, showing our design;

FIG. 2 is a front elevational view thereof;

FIG. 3 is a right side elevational view thereof, the left side elevational view being a mirror image of the side view shown;

FIG. 4 is a cross-sectional view taken in the direction of the arrows along line 4—4 of FIG. 2 thereof;

FIG. 5 is a top plan view thereof; and,

FIG. 6 is a bottom plan view thereof.
